UNITED STATES PATENT OFFICE.

JOHN A. MACMURCHY, OF WILKINSBURG, PENNSYLVANIA, ASSIGNOR TO THE WESTINGHOUSE MACHINE COMPANY, A CORPORATION OF PENNSYLVANIA.

ELASTIC-FLUID TURBINE.

1,212,975.

Specification of Letters Patent. Patented Jan. 16, 1917.

Application filed August 25, 1913. Serial No. 786,494.

To all whom it may concern:

Be it known that I, JOHN A. MACMURCHY, a subject of the King of Great Britain and Ireland, and a resident of Wilkinsburg, in 5 the county of Allegheny and State of Pennsylvania, United States of America, have made a new and useful Invention in Elastic-Fluid Turbines, of which the following is a specification.

10 This invention relates to elastic fluid turbines, and particularly to the construction of the stators or stationary elements of turbines.

An object of the invention is to provide 15 a new and improved stator or turbine casing in which means are employed for simplifying and cheapening the operation of manufacturing the casing, and also the operation of assembling the separate parts of 20 the turbine.

A further object is to produce a turbine 25 casing in which means are employed for eliminating difficulties ordinarily encountered in the casings of large turbines, and also for facilitating the operation of inspecting the interior of the turbine and of making necessary repairs within the working 30 passages of the turbine.

These and other objects I attain in a turbine 35 embodying the features herein described and illustrated in the drawings accompanying and forming a part of this application.

In the drawings: Figure 1 is a fragmental 40 sectional view of a turbine embodying my invention; and Fig. 2 is a sectional view of the turbine taken along the line 2—2 of Fig. 1 and looking in the direction of the arrows.

The turbine illustrated as an embodiment 45 of my invention comprises a rotor 3, a stationary casing 4, which surrounds the rotor, and internal rings 5 and 6, which are mounted on the casing and coöperate with the rotor in inclosing fluid passages of the 50 turbine. As illustrated, the casing 4 is substantially cylindrical and is divided, as is customary, on the horizontal plane passing through the axis of the rotor 3, thereby forming upper and lower portions, which 55 may be termed the top and bottom of the casing. The casing is also of simple construction, since it is formed throughout its length of metal of approximately the same thickness, and consequently it is not subject in the same degree to the temperature

strains encountered in casings of a massive construction which vary greatly in cross-section. The casing illustrated is provided on its inner face with circumferentially extending shoulders 7 and 8 adapted to be 60 employed in mounting the respective internal cylinders 5 and 6.

Each cylinder is formed in semi-circular sections so that each section may be secured to either the upper or lower portion of the 65 turbine casing, before the two parts of the casing are assembled or secured together. Each cylinder is provided on its outer or concave face with an annular flange or extension 9, which in turn is provided on its 70 outer edge with a projecting shoulder 10, adapted to engage a lateral face of one of the shoulders formed on the casing, and to be drawn into gripping engagement with the shoulder by means of a clamp ring 11. 75 Each clamp ring illustrated is formed in semi-circular sections and is mounted on the flange 9 of one of the internal cylinders so that the line of division between its sections coincides with the line of division between the sections of the cylinder. Any suitable means, such for example as bolts 12, which pass through the ring and are threaded into the flange of the cylinder, may be employed in mounting the ring on the flange 80 9 and in drawing it up into gripping engagement with one or the other of the cooperating shoulders 7 or 8 of the casing.

The internal cylinders 5 and 6 are preferably so mounted on the casing that the 85 line of division between the separate sections coincides with the line of division of the casing; or in other words, one half-section of each internal cylinder is mounted on one section of the casing, while the other 90 half-section is mounted on the other section of the casing. The clamp rings 11 may be centered either on the casing or on their mounting cylinders, and each cylinder is preferably centered on the cylindrical or 95 inner face of the casing shoulder with which it coöperates. It will be understood, however, that any other suitable means may be employed for centering the cylinders with relation to the casing and the rotor. 100

In the drawings I have shown a turbine equipped with a vane-carrying internal cylinder and an internal cylinder which is adapted to coöperate with the rotor elements in forming a fluid packing. The cylinder 5 105 110

embodies the first type of cylinder referred to and is provided with a plurality of circumferentially extending annular rows of fluid-directing vanes 13, which are adapted 5 to coöperate with circumferentially extending annular rows of working blades 14, mounted on the rotor 3. The cylinder 6 is provided with ribs or circumferentially extending projections 15, which interleave 10 with similar ribs or projections 16 on the rotor and coöperate with them to form what is ordinarily termed a labyrinth packing, which is adapted to prevent leakage of fluid from one chamber within the casing to another. The cylinder 6 illustrated may be provided with two sets of ribs or projections 15 and may therefore be employed in forming two separate packings, which may be spaced apart and may also be of different 15 diameters. In fact the cylinder 6 illustrated is of the form ordinarily employed in forming two separate packings, but is shown broken away for convenience of illustration. With such a construction, the cylinder 6, 20 in conjunction with the rotor, incloses an annular chamber 17, which may be employed in connection with a dummy or balance piston as a counter-balancing chamber. The separate sections of the internal cylinders 25 are shown secured together by means of tapered bolts 18, but it will be understood that any other suitable means may be employed.

The operation of mounting each internal 30 cylinder in place on the casing consists first, in so locating the separate sections that the flange 9 engages one of the casing shoulders, and then in drawing up the clamp ring 11, by means of the bolts 12, so that the casing 35 shoulder is gripped between it and the shoulder 10. With such a construction, the internal cylinders may be readily removed or replaced, and consequently the operation 40 of inspecting and repairing the interior passages of the turbine is greatly simplified. In addition to this, the internal rings are firmly and securely mounted in place on the turbine casing, without the necessity of providing cylinder mounting holes in the 45 casing.

In accordance with the provisions of the patent statutes, I have described the principle of operation of my invention, together with an apparatus which represents what I 50 now consider to be the preferred embodiment thereof, but I desire to have it understood that various changes, modifications,

substitutions and omissions may be made in the apparatus illustrated without departing from the spirit and scope of the invention, 60 as set forth by the appended claims.

What I claim is:

1. In a turbine, a casing divided on a plane passing through the axis of the rotor inclosed therein, an internal cylinder co-operating with the rotor and divided in semi-circular sections, and clamping means for removably securing each section of the internal cylinder to one of the sections of the casing. 70

2. In a turbine, an inclosing casing for the rotor of the turbine, an internal cylinder within the casing and surrounding the rotor, and means for removably clamping the cylinder to an imperforate part of the casing. 75

3. In a turbine, an inclosing casing for the rotor element of the turbine provided with a cylinder supporting shoulder on the inner face thereof, an internal cylinder mounted on said shoulder, and means for 80 gripping said shoulder and for removably securing the cylinder thereto.

4. In a turbine, an inclosing casing for the rotor element of the turbine, having an internal annular shoulder formed thereon, an internal cylinder located within the casing and surrounding and coöperating with the rotor element, and a clamp ring mounted on the internal cylinder for engaging the shoulder and for removably mounting the cylinder 90 on the casing.

5. In a turbine, an inclosing casing for the rotor of the turbine, having an imperforate cylinder-mounting shoulder formed thereon, an internal cylinder located within the 95 casing and surrounding the rotor, and means for clamping said cylinder to said shoulder.

6. In a turbine, an inclosing casing divided on a plane passing through the axis of the rotor inclosed within the casing, an 100 internal cylinder mounted on the casing and coöperating with the rotor in inclosing working passages of the turbine, said cylinder being divided in semi-circular halves, and means for clamping each half on a 105 shoulder formed on the interior of the casing.

In testimony whereof I have hereunto subscribed my name this 21st day of August, 1913.

JOHN A. MACMURCHY.
